UNITED STATES PATENT OFFICE.

GERMAIN BAPST AND LUCIEN FALIZE, OF PARIS, FRANCE.

DESIGN FOR A WATCH-CASE.

SPECIFICATION forming part of Design No. 17,012, dated December 7, 1886.

Application filed September 24, 1886. Serial No. 214,460. Term of patent 14 years. Patented in France August 24, 1886, No. 21,132.

To all whom it may concern:

Be it known that we, GERMAIN BAPST and LUCIEN FALIZE, citizens of the French Republic, residing at Paris, in the Department of the Seine, jewelers, have invented and produced a new and original Design for Watch-Cases, of which the following is a specification, reference being had to the accompanying drawings, forming part thereof.

10 Figure 1 is a front view, and Fig. 2 is a back view, of our newly-designed case, these two views being deemed necessary to fully illustrate our design.

15 On the back of the watch the chief subject is a representation of a grasshopper inclosed in a circle, around which is arranged an ornamental design composed of leaves, diagonal stems, and small flowers between two circular ribs. On the side of the dial the bezel is or-

20 namented with a similar arrangement of leaves, circular ribs, diagonal stems, and flowers, having within its circular outline a small seg- mental panel, as shown, said leaves, flowers,

and stems being countersunk into the surface, as shown.

25

We claim—

1. The ornamental design for a watch-case, consisting in the representation of a grasshopper in relief inclosed in a circle, substantially as shown.

30

2. In a design for a watch-case, the ornamentation of the bezel, consisting in a broken circle of flowers, leaves, and stems, having within its circular outline a small segmental panel, substantially as shown and described. 35

3. In a design for a watch-case, the ornamentation of the case, consisting in two circular ribs, diagonal stems, flowers at the ends of the stems, and leaves at the sides of the stems, in a range around between such ribs, substantially as shown and described. 40
